UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Application filed July 5, 1929. Serial No. 375,962.

My invention relates to a slicing machine and particularly to a slicing machine in which is employed a rotary knife, which may be motor driven, with which is used a work support guided for movement across the face and past the cutting edge of the knife. One object of my invention is to provide improved means for adjusting the angle of said work support. Other objects will appear from time to time in the course of the specification and claims.

I illustrate my invention more or less diagrammatically in the accompanying drawings, wherein—

15 Figure 1 is a front elevation;

Figure 2 is a side elevation with parts broken away;

Figure 3 is a front elevation of a variant form;

20 Figure 4 is a side elevation of a variant form; and

Figure 5 is a partial plan view.

Like parts are indicated by like symbols throughout the specification and drawings.

25 Referring first to the form of Figures 1 and 2, A generally indicates any suitable base or frame member mounted on supports A¹. Mounted on the base A is any suitable motor or transmission means, not herein shown, whereby the circular knife B is rotated. I indicate in association with said knife the knife shaft B¹ and the pulley B² about which passes the driving belt B³.

30 C generally indicates a guard plate for the front of the knife, the arcuate edge C¹ of the guard plate penetrating the front recess B⁴ in the knife.

D generally indicates a gauge plate structure which may be moved, in any suitable 35 manner, toward and away from the cutting plane in order to adjust the thickness of the slices.

E generally indicates a work supporting carriage mounted for example on the track E¹. It is provided with a depending portion E² in guiding relationship with the track E³. A certain adjustment of the position of the carriage is possible, about the rail E¹, by adjustment of the screw threaded elements 40 E⁴, which engage each side of the track E³.

I find it desirable to provide a work support which may be set at various angles. I have therefore provided a work support which is mounted on or supported upon the carriage E, but which may be positioned with its main supporting surface in a horizontal position, or may, selectively, be positioned with the said horizontal surface in inclined position. Referring to Figure 1 the upper portion or table E⁵ of the carriage E is provided with a plurality of channels or corrugations E⁶, herein shown as formed by intersecting plane surfaces E⁷. The table E⁵ is apertured or slotted as at E⁸, for a purpose which will later appear.

55 G generally indicates the work support with a main supporting surface G¹ and an abutment flange G², herein shown as at right angles thereto, positioned along the edge which is most remote from the cutting edge 60 of the knife at the initiation of the cutting stroke. It is upwardly extended as at G³, adjacent the cutting edge of the knife. The portion G³ is herein shown as connected, as 65 by the curved link G⁴, with the table E⁵ of the carriage. The link G⁴ is pivoted as at G⁵ and G⁶. G⁷ indicates a projection adjacent the intersection of the members G¹ and G², which is adapted to seat in the corrugations E⁶ as 70 shown in Figure 1. G⁸ indicates a spring, 75 anchored as at G⁹ on the carriage structure, with its opposite end secured as at G¹⁰, to the bottom of the member G. The aperture E⁸ is of sufficient size to permit the spring to 80 pass therethrough, as when it is in the dotted 85 line position in Figure 1.

I provide a pusher plate, generally indicated as H, slideable on the member G and away from the cutting plane. The plate H may be connected, as by the handle H¹ and its lateral extension H², to the bearing sleeve H³. Said bearing sleeve in turn is slideable along the guiding pin H⁴ which may be mounted as at H⁵ on the upward extension G³ of the flange G². It will be clear from Figure 1 90 that the link G⁴ is so formed as not to contact the sleeve H³ at any normal position thereof.

95 Referring to the form of Figures 3 to 5 inclusive I illustrate the carriage J provided 100

with a semi-cylindrical or partially cylindrical bearing portion J^1 , which is shown as having its inner and otherwise cylindrical surface knurled or roughened as at J^2 . This member J^1 is provided with one or more apertures J^3 .

Rotatable in relation to the member J^1 is the cylindrical or partially cylindrical member K the surface of which is roughened as at K^1 . Associated with it are the locking screws K^2 which pass through the apertures J^3 . K^3 are locking members, indicated as wing nuts, whereby the two members can be locked together to prevent their relative rotation.

Associated with the member K is the work support proper which includes the main work supporting member L with an abutment flange L^1 upwardly projecting from that edge thereof which is most remote from the cutting edge of the knife at the initiation of the cutting excursion. In the form indicated in Fig. 3 the members L and L^1 are connected to the member K along their abutting edges.

M generally indicates a pusher plate with its handle M^1 connected as by the member M^2 with the bearing sleeve M^3 slideable along the guiding pin M^4 which is secured as at M^5 to the member L^1 .

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

In slicing machines of the type herein described it is desirable to have a work support, movable with the carriage across the face of the knife, which support is adjustable in relation to the carriage. Some articles, such as bread, bacon and the like are best sliced when resting upon a broad horizontal surface such as that of the member G^1 , or L . When the meat support is tilted in the position in which it is shown in dotted line in Figure 3, or in dotted line in Figure 1, the space is insufficient to receive a piece of bacon for de-rinding or a piece of bread for de-crusting. The length of the bacon or of the bread loaf is such that if it is positioned on the carriage when the carriage is in the tilted position, the upper portion of the bacon or bread engages the cover member D^{10} and cannot be moved into cutting engagement with the knife.

On the other hand, as when cutting small articles or more or less soft articles such as sausage, it is advantageous to employ a trough which is V-shaped in cross-section, a trough such as is provided by the work sup-

port when it is in the tilted position, as shown in Figures 1 and 3. I obtain both results by providing a work support which may, at the election of the operator, be positioned in horizontal position or in inclined position. Referring to the form of Figures 1 and 2, the work support may normally be in the full line position. When in such position the member G^7 penetrates the groove or channel E^6 farthest to the left, referring to the parts in the position in which they are shown in Figure 1. The spring G^8 holds the work support clamped downwardly in the position in which it is shown in full line. When it is desired to tilt the work support it is simply lifted against the spring G^8 and the member G^7 is dropped into the desired groove or notch E^6 . The spring still serves to hold the parts locked in position, exerting tension upon the link G^4 .

In the form shown in Figures 3 and following a similar adjustment is obtained by merely loosening the wing nuts K^2 and rotating the cylindrical member K . This member may be of any desired radius and its center of rotation need not, as shown in Figure 3, conform to the corner or intersection of the members L , L^1 . Whereas I have illustrated the form in which two locking members are employed it will be realized that any desired number, two or more than two, can be employed. Two, however, is a convenient number and lends itself to the central location of the track E^1 in relation to the carriage J .

The characteristic application of my invention is generally stated as the employment of a direct locking connection between the work support and the carriage. For example in the form of Figures 1 and following the work support actually engages some one or another of the channels or grooves E^6 in the face of the carriage and the only locking means necessary are the means, for example the spring G^8 , for preventing movement of the abutting portions of work support and carriage. Similarly in the form of Figures 3 and following, the cylindrical abutment portion K , directly connected to the work support, is roughened for a direct locking engagement with the opposed concave abutment portion of the carriage. The function of the locking means, namely the screws and wing nuts shown for example in Figure 3, is to maintain this direct locking engagement between the opposed or abutting portions of work support and carriage. Adjustment of the carriage J about the rail E^1 is made possible by the adjusting screws J^5 threaded in the depending portion J^6 which engage the track E^3 .

I claim:

1. In a slicing machine having a knife and means for actuating it, a carriage and means for guiding it past the cutting edge of said knife, a work support mounted upon said

carriage and means for adjusting said work support selectively into a horizontal plane and into a plane inclined from the horizontal, including a link to which said work support is pivoted, said link in turn being pivoted to the carriage, a plurality of abutments on said carriage, and a member on said support adapted selectively to engage said abutments.

10 2. In a slicing machine having a knife and means for actuating it, a carriage and means for guiding it past the cutting edge of said knife, a work support mounted upon said carriage and means for adjusting said work support selectively into a horizontal plane and into a plane inclined from the horizontal, including a link to which said work support is pivoted, said link in turn being pivoted to the carriage, a plurality of abutments on said carriage, and a member on said support adapted selectively to engage said abutments, and yielding means for holding said carriage fixed in relation to the abutment with which it is for the time being associated.

15 3. In a slicing machine having a knife and means for actuating it, a carriage and means for guiding it past the cutting edge of said knife, a work support mounted upon said carriage and means for adjusting said work support selectively into a horizontal plane and into a plane inclined from the horizontal, the work support being tiltably mounted upon the carriage, the carriage being provided with a plurality of laterally spaced abutment

20 depressions, the work support being provided with means for penetrating and fitting in said depressions, and a flexible connection between the carriage and work support, adapted to permit the work support to be

25 positioned selectively in operative engagement with any one of a plurality of said abutments.

4. In a slicing machine having a knife and means for actuating it, a carriage and means for guiding it past the cutting edge of said knife, a work support mounted upon said carriage and means for adjusting said work support selectively into a horizontal plane and into a plane inclined from the horizontal, the work support being tiltably mounted upon the carriage, the carriage being provided with a plurality of laterally spaced abutment depressions, the work support being provided with means for penetrating and fitting in said depressions, and a flexible connection between the carriage and work support, adapted to permit the work support to be positioned selectively in operative engagement with any one of a plurality of said abutments, and yielding means adapted to hold said carriage fixed in relation to the abutment with which it is for the time being associated.

5. The structure of claim 4 characterized by the employment of a link connection be-

tween the carriage and work support, and a spring interposed between the carriage and work support, the abutments being positioned between said link connection and said spring.

Signed at Indianapolis, county of Marion and State of Indiana, this 26th day of June, 1929.

WILLIAM J. CAMPBELL.
